(57) **CLAIM**

We claim the ornamental design for a photocoagulator table, as shown and described.

DESCRIPTION

FIG. 1 is a perspective view of a photocoagulator table showing the new design;

FIG. 2 is a side view thereof;

FIG. 3 is an opposing side view thereof;

FIG. 4 is a front view thereof;

FIG. 5 is a back view thereof;

FIG. 6 is a top view thereof; and,

FIG. 7 is a bottom view thereof.

The broken lines illustrated in FIGS. 1–7 represent environmental structure, which is not considered a part of the claimed design.
